UNITED STATES PATENT OFFICE.

DANIEL M. O'BRIEN, OF SAYRE, PENNSYLVANIA.

VENTILATOR FOR SHOES.

1,392,350.

Specification of Letters Patent.

Patented Oct. 4, 1921.

Application filed May 1, 1919. Serial No. 293,909.

To all whom it may concern:

Be it known that I, DANIEL M. O'BRIEN, a citizen of the United States, residing at Sayre, in the county of Bradford and State 5 of Pennsylvania, have invented certain new and useful Improvements in Ventilators for Shoes, of which the following is a specification.

This invention relates to an improved shoe 10 ventilator and has as one of its objects to provide a device of this character which may be readily applied at any approved point on the upper of a shoe for ventilating the shoe.

The invention has as a further object to 15 provide a ventilator which will be neat and unobtrusive in appearance so that the presence of the device upon a shoe will not mar the sightliness of the shoe.

The invention has as a still further object 20 to provide a ventilator which will be of extremely simple construction and wherein, if desired, two or more of the ventilators may be employed upon a shoe and so arranged that movement of the foot within the shoe, 25 incident to the operation of walking, will tend to set up a circulation of air through the shoe.

And the invention has as a still further object to provide a ventilator which may, if 30 desired, be employed for securing an ornament such as a bow, upon a shoe.

Other and incidental objects will appear hereinafter. In the drawings:

Figure 1 is a side elevation showing a conventional type of shoe equipped with a pair 35 of my improved ventilators,

Fig. 2 is a sectional view taken on the line 2-2 of Fig. 1 and more particularly illustrating the construction and mounting of 40 the device.

Fig. 3 is a perspective view showing the device in detail, the stud and cap employed being separated,

Fig. 4 is a side elevation showing the use 45 of my improved device for securing a bow upon a slipper, the slipper being conventionally illustrated,

Fig. 5 is a view particularly illustrating the plate employed for holding the bow, and

Fig. 6 is a sectional view showing the manner 50 in which the ventilator clamps the bow upon the plate as well as secures the plate and bow upon a slipper.

In carrying the invention into effect, I 55 employ a tubular stud 10 provided at its inner end with a head 11. Removably

threaded upon the stud at its outer end is a cap 12 and preferably, the periphery of this cap is milled so that the cap may be easily rotated. As particularly shown in 60 Fig. 2, the cap is provided with an axial screw threaded socket to receive the outer end of the stud and leading from this socket is a reduced axial opening 13 registering with the opening through the stud.

In Fig. 1, I have shown a pair of my improved ventilators upon a conventional type of shoe 14. At least two ventilators are 65 preferably employed and, as shown in this figure, one of the ventilators may be mounted at the inner side of the toe of the shoe a short distance above the toe while the other may be arranged at the inner side of the shoe medially with respect to the shank and 70 preferably just above the shank. In mounting the ventilator, an opening of proper size is first punched through the leather of the shoe, when the stud 11 is then inserted through this opening from the inner side of 75 the shoe. The cap 12 is then applied to the outer end of the stud and adjusted to tightly bind the ventilator in position. In this connection it should be observed that when forming the ventilator receiving openings in the shoe care should be taken that 80 such openings will each be of a size to snugly receive the ventilator stud therethrough and preferably, a special punch will be provided for forming these openings. As will be 85 noted, a pair of the ventilators when applied 90 to a shoe, as shown in Fig. 1, will not detract from the appearance of the shoe.

Movement of the foot within the shoe, incident to the operation of walking will, of course, tend to draw air in through one of 95 the ventilators and expel the air from the other of the ventilators. Consequently, a circulation of air within the shoe will be had for effectually ventilating the shoe.

In Figs. 4, 5 and 6 of the drawings, I 100 have illustrated a slight modification of the invention showing the use of my improved ventilator as an ornament securing device. A plate 15 is employed. This plate may be formed from a piece of suitable resilient 105 sheet metal and is provided adjacent opposite ends thereof with openings 16. Lapped back and forth across the front face of the plate is a piece of ribbon forming a bow 17. The ends of the ribbon are inserted 110 through the openings 16 in the plate when the overlapping portions of the bow are all

stitched together at their edges medially of the bow. In this way, a bow may be readily formed from a piece of ribbon while, at the same time, the bow will be fastened to the plate 15. Furthermore, it will be observed that the plate will be obscured by the bow. The plate with the bow attached is then ready to be secured upon a slipper and, in Fig. 4, I have shown the bow fastened upon a conventional slipper 18. This is accomplished by first inserting the ventilator stud 10 through the upper end portion of the slipper vamp, as shown in detail in Fig. 6. The plate 15 is then fitted over the stud, this plate being formed centrally with a suitable opening to freely receive the stud while the bow 17 is also formed with an opening to register with the opening of the plate. The ventilator cap is then threaded down upon the stud for connecting the ventilator with the shoe and clamping the plate upon the stud. Thus, the ventilator will support the bow in the usual position upon the slipper while, at the same time, the ventilator will act to admit air within the slipper. Furthermore, it will be seen that the ventilator cap will bind against the material of the bow so as to prevent possible lateral shifting of the bow upon its supporting plate and will also form, in effect, an ornamental button centrally of the bow so as to produce a very pleasing appearance. Also, it is to be particularly observed that owing

to the soft and pliable nature of the material of the bow, the bow fabric will coat with the 35 ventilator cap to prevent retrograde movement thereof upon the stud of the ventilator and will tend to lock the cap in position upon the stud binding the ventilator upon the shoe and securely holding the plate 15 40 to support the bow extending transversely of the slipper.

Having thus described the invention, what is claimed as new is:

The combination with a shoe, of a plate 45 bearing against the outer surface of the shoe near the toe portion thereof and provided with spaced transverse slots and an intermediate opening, a ribbon threaded through the slots and over the opening 50 to form a bow, an exteriorly threaded stud extending through the opening in the plate and piercing the ribbon, said stud being provided throughout its length with an aperture communicating with the interior of the 55 shoe and having an enlarged head bearing against the inner surface of said shoe, and an internally threaded cap engaging the exterior threads of the stud and provided with an aperture registering with the aperture 60 in the stud, said cap bearing against the ribbon and serving to clamp the bow, plate and stud in position on the shoe.

In testimony whereof I affix my signature.

DANIEL M. O'BRIEN. [L.S.]
